UNITED STATES PATENT OFFICE

DARIO BUCCICONE, OF GARY, INDIANA

PACK OPENING MACHINE

Application filed October 25, 1930. Serial No. 491,286.

This invention relates to pack opening machines and has for one of its objects the provision of a machine of this class which will thoroughly flex and work a hot rolled pack of metal sheets so as to open or separate the several sheets of the pack without marking or otherwise damaging the sheets.

Another object is to provide a machine in which the feed-out pinch-rollers are maintained out of pinching engagement with the pack while the pack is in the bite of the feed-in pinch-rollers, thereby materially reducing the power required to operate the machine.

In the drawings:

Figure 1 is a plan of a pack opening machine constructed in accordance with this invention.

Figure 2 is a sectional elevation on the line II-II of Figure 1.

Referring more particularly to the drawings, the numeral 2 designates the base of the machine which supports a pair of spaced side housings 3 provided with windows or bearing guideways 4 and 5 adjacent the entering and discharge sides of the machine, respectively. A pair of bearing blocks 6 and 7 are slidably mounted in each of said guideways and pinch-rollers 8 and 9 are journaled in the bearing blocks at the entering side of the machine, while pinch-rollers 10 and 12 are journaled in the bearing blocks at the discharge or exit side of the machine.

The top bearing blocks 6 and the pinch-rollers 8 and 10 journaled therein are normally resiliently held against vertical displacement by means of stiff links 13 which are pivotally connected to the top bearing blocks and to levers 14 which extend parallel to the top face of each housing 3. The levers 14 are pivoted to brackets 15 at the entering side of each housing 3 and their other ends are provided with lugs 16 which engage coiled springs 17 mounted in spring retaining cups 18 carried by brackets 19. The springs 17 are adjustable by followers 20 and set-screws 21. The ends of the levers 14 have their free ends connected by a cross-bar 22.

In operation, when a pack of sheets enters the bite of the pinch-rollers 8 and 9 the top roller 8 will be forced to move upwardly a

distance equal to the thickness of the pack. This movement of the top roller 8 is communicated through the stiff links 13 to the levers 14 which, due to their length, will multiply such movement and lift the top 55 pinch-roller 10 through the stiff links 13 against the pressure of the springs 17.

The amount of movement or lift imparted to the top pinch-roller 10 will be materially greater than that imparted to the roller 8 by the pack so as to separate the pinch-rollers 10 and 12 a sufficient distance to permit free passage of the packs therebetween while the pack is in the bite of the rollers 8 and 9. When the pack has moved from between the 65 rollers 8 and 9 the springs 17 and gravity will force the levers 14 to drop and force the pinch-roller 12 to bite the pack and feed it out of the machine.

A pair of pack opening rolls 25 are journaled in suitable bearings 26 mounted in windows 27 in the housings 3 intermediate the pairs of pinch rollers. The bearings 26 are locked against vertical displacement by means of filler blocks 27^a and cap pieces 27^b.

The rolls 25 are fluted spirally so as to form alternate longitudinally extending spiral grooves and blades 28 and 29, respectively. The rolls 25 are spaced vertically so that the blades 29 of one roll mesh with the 80 grooves 28 of the other roll, whereby a pack upon being fed into the bite of the rolls 25 will be bent in alternate directions on a line at an angle to the longitudinal and transverse axis of the pack. This bending of the 85 pack will result in breaking of the bond between all of the sheets of the pack.

Due to the fact that only curved surfaces of the blades engage the pack and such surfaces engage the pack on an angle and with 90 a more or less rubbing action, as contrasted with the beating action of pack openers of this general class, the sheets of the pack are not marred or marked and, therefore, are just as satisfactory as hand opened sheets.

The pinch-rollers 8 and 9 and 10 and 12 are positioned close to the opening rolls 25 so as to eliminate the necessity for guides between the pinch-rollers and opening rolls, thereby eliminating another cause of mark- 100

ing the sheets in the machines heretofore generally used. When guides are used the sheets are bent down or up against the edges of the guides by the action of the beaters, 5 bending or crimping rolls, and are thereby marked in such manner as to destroy their finish.

The pinch-rollers 8 and 9 and 10 and 12 are provided with long tooth meshed gears 10 35 and 36, respectively, at one end to cause the rollers of each pair to rotate together and the teeth of the gears are of such length that the gears will remain in mesh when the rollers are separated by the packs passing 15 therebetween. The shafts of the top rollers 8 and 10 are extended beyond the gears 35 and 36 and are provided with sprockets 37 over which a drive chain 38 is trained to cause a simultaneous drive of all the pinch- 20 rollers.

The roller 8 is provided with a gear 39 at its end opposite the gear 35 which is meshed with a gear 40 of a worm and worm-wheel speed reducing unit 41 which is coupled to 25 and operated by a motor 42.

The opening rolls 25 are provided with meshed gears 43 which cause said rolls to rotate in unison and the top one of the rolls 25 has one of its journal ends extended and 30 coupled to a motor 44.

It will be understood that if desired a single motor may be used to drive both the pinch-rollers and opening rolls by connecting such motor to both the pinch-rollers and opening rolls through suitable gearing.

While I have shown and described one specific embodiment of my invention it will be understood that I do not wish to be limited thereto since various modifications may 40 be made without departing from the scope of my invention, as defined in the appended claims.

I claim:

1. A pack opening machine comprising a 45 base, a pair of spaced side housings, vertically disposed guideways in said housings adjacent the entering and discharge sides thereof, bearings in said guideways, at least the upper one of said bearings in each guideway 50 being vertically slideable in said guideway, entering pinch-rollers journaled in the bearings mounted in said guideways adjacent the entering side of the machine, discharge pinch-rollers journaled in the bearings in the other 55 pair of guideways adjacent the discharge side of the machine, means for automatically raising the top roller of said discharge pinch-rollers when a pack is entered between said entering pinch-rollers, said means comprising 60 levers extending along the top of each of said housings and pivoted thereto adjacent the entering side of the machine, stiff links pivotally secured to said levers adjacent the pivotally mounted end thereof and sus- 65 pendingly supporting the upper bearings for

the upper entering pinch-roller, other stiff links pivotally secured to said levers adjacent the free ends thereof and suspendingly supporting the upper bearings for the upper discharge pinch-roller, spring means for normally biasing the said levers and upper pinch-rollers downwardly toward the lower pinch-rollers, and a pair of opening rolls journaled in said housings intermediate said pairs of pinch-rollers. 70

2. A pack opening machine comprising a base, a pair of spaced side housings, vertically disposed guideways in said housings adjacent the entering and discharge sides thereof, bearings in said guideways, at least the upper one of said bearings in each guideway being vertically slideable in said guideway, entering pinch-rollers journaled in the bearings mounted in said guideways adjacent the entering side of the machine, discharge 80 pinch-rollers journaled in the bearings in the other pair of guideways adjacent the discharge side of the machine, means for automatically raising the top roller of said discharge pinch-rollers when a pack is entered 85 between said entering pinch-rollers, said means comprising levers extending along the top of each of said housings and pivoted thereto adjacent the entering side of the machine, stiff links secured to said levers ad- 90 jacent the pivotally mounted end thereof and suspendingly supporting the upper bearing for the upper entering pinch-roller, other stiff links secured to said levers adjacent the free end thereof and suspendingly support- 95

ing the upper bearing for the upper discharge pinch-roller, means for normally biasing said levers and upper pinch-rollers downwardly toward the lower pinch-rollers and a pair of opening rolls journaled in said housings intermediate said pairs of pinch-rollers, said pinch-rollers being positioned close to said opening rolls so as to feed the packs to and receive the packs from said rolls without the aid of guides. 100

3. A pack opening machine comprising a base, a pair of spaced side housings, vertically disposed guideways in said housings adjacent the entering and discharge sides thereof, bearings in said guideways, at least the upper one of said bearings in each guideway being vertically slideable in said guideway, entering pinch-rollers journaled in the bearings mounted in said guideways adjacent the entering side of the machine, discharge 110 pinch-rollers journaled in the bearings in the other pair of guideways adjacent the discharge side of the machine, means for automatically raising the top roller of said discharge pinch-rollers when a pack is entered between said entering pinch-rollers, said means comprising levers extending along the top of each of said housings and pivoted thereto adjacent the entering side of the machine, stiff links secured to said levers ad- 115 jacent the pivotally mounted end thereof and suspendingly supporting the upper bearing for the upper discharge pinch-roller, other stiff links secured to said levers adjacent the free end thereof and suspendingly support- 120

ing the upper bearing for the upper discharge pinch-rollers journaled in the bearings in the other pair of guideways adjacent the discharge side of the machine, means for automatically raising the top roller of said discharge pinch-rollers when a pack is entered 125 between said entering pinch-rollers, said means comprising levers extending along the top of each of said housings and pivoted thereto adjacent the entering side of the machine, stiff links secured to said levers ad- 130

10 jacent the pivotally mounted end thereof and suspendingly supporting the upper bearing for the upper entering pinch-roller, other stiff links secured to said levers adjacent the free end thereof and suspendingly supporting the upper bearing for the upper discharge pinch-roller, springs engaging said levers adjacent the free ends thereof and normally biasing said levers and upper pinch-rollers downwardly and a pair of opening rolls journaled in said housings intermediate said pairs of pinch-rollers.

15 In testimony whereof, I have hereunto set my hand.

15 DARIO BUCCICONE.
